EDWARD H. BELDEN, OF TOLEDO, OHIO, ASSIGNOR TO BELDEN PATENTS INCORPORATED, OF TOLEDO, OHIO, A CORPORATION OF OHIO.

COUNTERBALANCED-PISTON MOTOR.

Application filed December 21, 1923. Serial No. 682,002.

My invention relates to an internal combustion motor, and more particularly to a motor of the two-cycle type having a charging cylinder preferably parallel with the working cylinder.

The object of my invention is to provide a compact and efficient motor which will operate with a minimum of noise and vibration.

10 Referring to the accompanying drawings, which illustrate a motor embodying my invention:

Fig. 1 is a side view of a motor, with parts broken away. Fig. 2 is a transverse 15 vertical section on the line 2—2 of Fig. 1.

Fig. 3 is a horizontal section on the line 3—3 of Fig. 2.

Figs. 4 and 5 are diagrammatic views showing different positions of the working 20 parts.

A crank case 8 has attached journals 9, 10, in which is mounted a crank shaft 11, having three cranks 12, 13, 14. Near the top and to one side of the crank case there is mounted 25 a fulcrum shaft 15, having pivoted thereon three one armed levers 16, 17, 18. These levers may be extended past the fulcrum to bear counter-balancing weights 16', 17', 18', but only one arm of each lever is connected 30 to working parts of the motor. Links 19, 20, 21 connect the cranks to the levers, link 19 being pivoted to lever 16 at 22, as shown, and links 20 and 21 being similarly pivoted to levers 17 and 18, respectively.

35 There is a pair of cylinders, pistons, and associated parts in connection with each lever, but they are duplicates and so only those in connection with lever 16 will be described in detail.

40 A working cylinder 23 has therein a piston 24, connected by a rod 25 to a pivot 26 on the lever 16 between its fulcrum and the pivot 22. An exhaust port 27 opens from the side of the cylinder at a point where it will be uncovered near the end of 45 the working stroke of the piston. A head 28 covers the upper end of the cylinder and has a cavity 29 opening directly into the cylinder.

50 A charging cylinder 30 is located at one side of and parallel with the working cylinder. The charging cylinder has therein a piston 31, connected by a rod 32 to the lever 16 at a point 33 more distant from the fulcrum than the pivot 22, to which the

crank is connected. An intake port 34 in the side of the charging cylinder is connected to any suitable source of fuel gas supply, and is uncovered by the downward movement of the piston. The head 28 is provided with 60 a check valve 35, urged towards its seat by a spring 36 to prevent the passage of gases from the cavity 29 into the charging cylinder, while permitting their passage in the other direction.

65 A spark plug 37 is provided for firing the charge, and is connected to a suitable ignition system, the timer of which is indicated at 38. A water jacket 39 with lead off pipe 40 is indicated, and may be of any suitable 70 type. The motor is shown as adapted for use in an automobile, the usual fan belt 41 being indicated as driven by a pulley 42 on an end of the crank shaft, while a fly wheel 43 is mounted on the other end of the shaft 75 and is provided with teeth 44 for driving parts, such as an oil pump located in the casing at 45. These and other common features of cooling, ignition, oiling, and self-starting systems, etc., are used with the 80 motor in an automobile, but need not be further described, as they form no part of my invention.

85 The operation of my motor is as follows: With the parts as shown in Fig. 2, a charge previously compressed within the cavity 29 and upper end of the working cylinder is ignited by the spark plug. Return of gases into the charging cylinder is prevented by check valve 35 so that the full 90 force of the explosion is exerted in driving piston 24 downward. Rod 25, lever 16, rod 32 and piston 31 necessarily move downward in response to the motion of piston 24. Downward motion of piston 31 rarifies any 95 fuel gases remaining within the charging cylinder. When port 27 is uncovered by the downward movement of piston 24, compression within the working cylinder is relieved and the products of combustion are exhausted. In the meantime, descent of piston 31 has uncovered port 34 and allowed fuel 100 gases to rush in and fill the charging cylinder. As the connected crank 12 continues to rotate, the pistons are forced back up, driving the charge from the charging cylinder and compressing it within the cavity 29 in the head and the upper end of the working cylinder, ready to be ignited when the 105 pistons reach the upper limits of their 110

strokes. The parts have then returned to the position shown in Fig. 1.

I prefer to leave but little clearance between the piston 31 in its upper position and the end of the cylinder, so that nearly all of the charge is driven from the charging cylinder into the working cylinder. This enables the use of a smaller charging cylinder than could be used if more of the charge remained in it, and also results in a higher vacuum during the down stroke of the piston. This high vacuum produces a rapid and turbulent inrush of fuel gases, whereby the charge is more thoroughly and evenly mixed than it would be with slower movement of the gases.

The pivot 26 to which piston 24 is connected oscillates in a path, indicated in Fig. 2 by dotted line 46, which approaches but does not cross the axial line of the working cylinder 23, indicated in Fig. 2 by dotted line 47. In a similar manner pivot 33, connected to piston 31, moves in a path, indicated on Fig. 2 by dotted line 48, which lies entirely on one side of the axial line of the charging cylinder, indicated on Fig. 2 by dotted line 49. The result is that thrust by the piston rods always urges the pistons against the same walls of their respective cylinders, and does not slap the piston from side to side in the cylinder. Where the cylinder is vertical, it is immaterial, so far as piston slap is concerned, on which side of the axial line the rod remains.

The pressure of the gases being compressed during the upstroke of piston 24 urges that piston in the same direction as the ignited gases drive it during the working stroke, and the resultant stresses in the connected joints are in the same direction as those produced by gravity, which obviates the tendency of slightly loosened joints to knock under changing stresses.

If the link from the crank were connected to a point on the lever between its fulcrum and the pivot to which the working piston is connected, the stress of the working stroke would tend to raise the fulcrum end of the lever, but this is obviated by positioning the crank connection 22 farther from the fulcrum than the connection 26 of the working piston.

The three working cylinders operate in precisely the same way, but at intervals evenly dividing each revolution of the crank, resulting in a continuous overlapping torque on the crank shaft similar to that resulting from the usual arrangement in a six-cylinder, four-cycle engine. As will be seen, the axis of the crank is to one side of the axes of the working cylinders, and the working stroke of each piston occurs while the crank is on the side of its shaft nearest the axis of the piston.

In some instances a single working cyl-

inder might suffice, and any desired plural number may be connected to a crank shaft in any usual or obvious way. For some purposes, a valved intake port near the exit end of the charging cylinder may be used, 70 and various other changes within the scope of the appended claims may be made without departing from the spirit of the invention.

The weights 16', 17' and 18' may be used 75 or not, as desired, and may be made of proper weight to accomplish the desired purpose. These weights have several functions.

I prefer to arrange each weight so its center of gravity will be in a line passing 80 through the axis of the fulcrum and the center of momentum of the other end of the lever. In calculating this center of momentum, the movements of the connected links should be considered. A weight of 85 proper size so arranged will balance the stresses exerted on the crank case in starting and stopping the working arm of the lever, as the weight moves in the opposite direction from the center of momentum of the 90 arm.

The weights have a further steadyng effect similar to that of a balance wheel. Energy is stored in the weight by changing it from a stationary condition to one of maximum 95 motion during the first part of the explosion stroke, when the pressure on the piston is heaviest. This energy is expended by stopping the motion of the weight during the second half of the stroke, when the pressure on the piston is lessening. In this way the effective force of the working stroke is more evenly distributed. Likewise, energy is stored in the weight during the first half 100 of the compression stroke, when the movement of the piston is but slightly resisted by the gases, and this energy is expended during the second half of the compression stroke, when the compression is greatest.

As will be seen, this steadyng effect is similar to that of a balance wheel, but is not the same. A balance wheel has no effect except as the speed of the crank shaft changes, and so can only dampen the vibrations due to successive explosions, whereas the oscillating weights change their speeds, and so exert their steadyng effect, regardless of the speed of the crank shaft. A balance wheel lessens the variation in speed due to successive blows of the pistons, while the weights 110 change the blows to pushes. A balance wheel does not lessen, but, if anything, increases the strain to which the crank shaft and pitman are subjected, while the oscillating weights lessen the strain on the crank 115 shaft and pitman at the time the strain is greatest. For these reasons, the use of the weights makes possible the use of lighter crank shaft and pitmans. The weights increase the strain upon the lever fulcrum, but 120

125 130

this is a stationary part which may be made as strong and heavy as necessary without appreciable increase in cost and without affecting the vibrations.

It will be seen, therefore, that the weights are extremely efficient in reducing vibrations and making the motor run smoothly.

Some of the features of this invention are disclosed and claimed in my copending applications Serial Nos. 682,011 and 682,001, filed December 21, 1923, and I do not claim herein matters which can be claimed in that application.

What I claim is:

1. In an internal combustion motor, a working cylinder having an open end, a lever fulcrumed beyond and at one side of said end, the fulcrum being at an end of the lever, a charging cylinder parallel with and on the other side of the working cylinder, pistons in the cylinders, and rods connecting the pistons to the lever.

2. In an internal combustion motor, a working cylinder having an open end, a lever fulcrumed beyond and at one side of said end, the fulcrum being at an end of the lever, a charging cylinder parallel with and on the other side of the working cylinder, pistons in the cylinders, rods connecting the pistons to the lever, a crank shaft, and a link connecting a crank on the shaft to a point on the lever between the points at which said rods are attached.

3. In an internal combustion motor, a vertical working cylinder open at its lower end, a lever fulcrumed below and at one side of said open end, a charging cylinder parallel with and on the other side of the working cylinder, pistons in the cylinders, rods connecting the pistons to spaced points on the lever, a crank below the lever and a link connecting the crank to a point on the lever between those at which said rods are attached.

4. In an internal combustion motor, a working cylinder having an open end, a lever fulcrumed beyond and at one side of said end, the fulcrum being at one end of the lever, a charging cylinder parallel with

and on the other side of the working cylinder, there being a port connecting the closed end of the working cylinder with the adjacent end of the charging cylinder, pistons in the cylinders, and rods connecting the pistons to the lever.

5. In an internal combustion motor, a vertical working cylinder open at its lower end, a lever fulcrumed below and at one side of said end, a charging cylinder parallel with and on the other side of the working cylinder, pistons in the cylinders, and rods connecting the pistons to the lever.

6. In an internal combustion motor, a vertical working cylinder, a charging cylinder at one side of and parallel with the working cylinder, pistons in the cylinders, a crank shaft on the side of the axial line of the working cylinder distant from the charging cylinder, and connections between a crank on the shaft and the pistons whereby the crank is on the side of the shaft nearest the axial line of the working cylinder during the working stroke.

7. In an internal combustion motor, a plurality of parallel vertical working cylinders having their axes in the same plane, an associated equal number of charging cylinders having their axes in a plane parallel to that of the working cylinders, there being a port connecting the top of each working cylinder with its associated charging cylinder, a lever beneath each pair of cylinders, a piston in each cylinder, rods connecting the pistons to the levers, a crank shaft beneath the levers, and links connecting cranks on the shaft to the levers at points between the attachments of the respective working and charging piston rods.

8. In an internal combustion motor of the two-cycle type, a working cylinder and piston, a charging cylinder and piston, a lever, a crank shaft, means connecting an arm of the lever to the pistons and crank shaft, and a counterbalancing weight oscillating in the opposite direction from the lever arm.

In testimony whereof I have hereunto signed my name to this specification.

EDWARD H. BELDEN.
